METHOD OF FORMING CAST HOLLOW ARTICLES

Loyal L. Johnston, Zelienople, Pa., assignor to Herman Pneumatic Machine Company, Pittsburgh, Pa., a corporation of Pennsylvania

Original application February 18, 1946, Serial No. 648,318. Divided and this application July 29, 1948, Serial No. 41,421

3 Claims. (Cl. 22—200.5)

1

This invention relates to a method of forming cast hollow articles and particularly such a method which involves the centrifugal casting of the articles. My method includes the formation of a hollow mold out of compactable mold forming material and the centrifugal casting of the hollow article in the mold. This application is a division of my Patent No. 2,449,900.

My method is a departure from methods of forming cast hollow articles heretofore employed and enables greatly increased production and economy. The invention will be described for purposes of explanation and illustration as practiced in the centrifugal casting of pipe, such, for example, as soil pipe, and in the formation of molds for the centrifugal casting of such pipe. It is to be understood, however, that the invention has other uses.

I provide a method of forming cast hollow articles whereby unprecedentedly rapid and economical manufacture of such articles is made possible. I preferably employ a flask which is selectively positionable in generally vertical and in generally horizontal position. Desirably the flask is positioned vertically while mold forming material is introduced into it, whereupon it is shifted to horizontal position. The flask is rotated and mold forming material therein is compacted and shaped. I prefer to operate on the mold forming material in the flask successively by means removing a portion of the mold forming material in the flask and providing an opening therein and means compacting and shaping the remaining mold forming material in the flask. The means for removing a portion of the mold forming material and providing an opening in such material may, for example, comprise a screw conveyor. The means for compacting and shaping the mold forming material in the flask may comprise a mandrel which is desirably mounted for rotation so that when it is acting on the mold forming material in the flask it will rotate due to frictional engagement therewith. While the mandrel may be driven in its rotary movement it is preferably not driven but rather caused to rotate by frictional engagement with the mold forming material.

The flask is preferably mounted in a support which is movable between a position in which the flask is generally vertical and a position in which the flask is generally horizontal. Desirably the means for rotating the flask is continuously operable for all positions of the flask, i. e., when the flask is in generally vertical position, when it is in generally horizontal position and when it is

2

in any intermediate position. Desirably rotation of the flask is continuous through the period during which it is moved from generally vertical position to generally horizontal position.

15 The means for removing a portion of the mold forming material in the flask to provide an opening therein and the means for compacting and shaping mold forming material in the flask are preferably mounted so that each thereof may, as desired, be brought into position coaxial with the flask and then advanced therewith. For example, such means may be mounted on a carriage operable on a guideway substantially parallel to the axis of the flask when the flask is in generally horizontal position. Such means may be carried by a carrier movable relatively to the carriage transversely of the direction of movement of the carriage.

20 Means are provided for delivering mold forming material into the flask when the flask is in generally vertical position. Means are also provided for stripping the casting from the flask and loosening and removing mold forming material therefrom.

25 Novel operating mechanism is provided for the various portions of the apparatus above referred to whereby exceptionally rapid, accurate and economical operation is obtained.

In practicing my method of forming a cast hollow article I preferably compact finely divided mold forming material to form a hollow open-ended mold, rotate the mold, introduce molten material into the rotating mold through one end thereof to form by centrifugal casting a hollow article, turn the mold in place to generally upright position and discharge the article from the mold through the opposite and lower end thereof. While such a method broadly is of great utility and contributes largely to the unprecedented economy of manufacture which I obtain, I find it desirable to introduce mold forming material downwardly into an elongated open-ended flask when the flask is disposed in generally upright position, compact the mold forming material within the flask to form a hollow mold, rotate the mold, introduce molten material into the rotating mold through one end thereof to form by centrifugal casting a hollow article and, with the flask disposed in generally upright position with the end uppermost which was uppermost when the mold forming material was introduced downwardly therewith, discharge the article from the flask through the lowermost end thereof.

30 35 40 45 50 55 More specifically I prefer to form a cast hollow article by introducing mold forming material

downwardly into an elongated open-ended flask when the flask is disposed in generally upright position, compact the mold forming material within the flask to form a hollow mold, dispose the flask in generally horizontal position, rotate the flask, introduce molten material into the mold in the rotating flask through one end of the flask to form by centrifugal casting a hollow article, dispose the flask in generally upright position with the end uppermost which was uppermost when the mold forming material was introduced downwardly thereinto and with the flask so disposed discharge the article from the flask through the lowermost end thereof.

I further provide a method of forming a cast hollow article comprising introducing mold forming material into an elongated open-ended flask, compacting the mold forming material within the flask to form a hollow mold, maintaining the mold forming material in the flask by pressing thereagainst generally axially of the flask and rubbing thereagainst at at least one end of the flask, rotating the flask and introducing molten material into the flask to form by centrifugal casting a hollow article. Desirably the mold forming material is introduced downwardly into the flask when the flask is disposed in generally upright position and the article is discharged from the flask through the lowermost end thereof with the flask disposed in generally upright position with the end uppermost which was uppermost when the mold forming material was introduced downwardly thereinto.

Other details, objects and advantages of the invention will become apparent as the following description of certain present preferred methods of practicing the same proceeds.

In the accompanying drawings I have illustrated certain present preferred methods of practicing the invention, in which

Figure 1 is an elevational view, partly in central vertical cross section, of centrifugal casting apparatus;

Figure 2 is a plan view of the apparatus shown in Figure 1;

Figure 3 is a fragmentary end view of the apparatus shown in Figures 1 and 2 as viewed from the right hand end thereof, but to enlarged scale;

Figure 4 is a view similar to Figure 3 looking from the opposite end;

Figure 5 is an end view of the flask and associated mechanism as viewed from the right hand end thereof with reference to Figure 1, but to enlarged scale and partly in vertical transverse cross section;

Figure 6 is a fragmentary cross sectional view to enlarged scale of a portion of the structure shown in Figure 1 showing a section of pipe as cast in the mold;

Figure 7 is a fragmentary side elevational view of a modified form of centrifugal casting apparatus; and

Figure 8 is a vertical transverse cross sectional view taken on the line VIII—VIII of Figure 7.

Referring now more particularly to the drawings, there is provided a base or frame 2 having parallel spaced upward projections 3 carrying coaxial bearings 4 and 5. Journaled in the bearing 4 is a trunnion 6. Keyed to the trunnion 6 is an arm 7 whose outer end is pivoted at 8 to a piston rod 9 connected with a piston in a cylinder 10 pivotally mounted at 11 in brackets 12. The piston in the cylinder 10 is operated by any suitable fluid under pressure. Movement of the piston in the cylinder swings the arm 7 about

the axis of the trunnion 6, and since the arm is keyed to the trunnion this results in turning of the trunnion 6 in the bearing 4.

The bearing 5 carries a bearing sleeve 13 which is longer than the bearing, extending inwardly relatively thereto, or toward the bearing 4. Journaled in the sleeve 13 is a shaft 14 connected through a gear reducer 15 and a coupling 16 to an electric motor 17 which drives the shaft 14. Another shaft 14a coaxial with the shaft 14 but projecting from the opposite end of the motor 17 and driven by the motor may drive another unit similar to that shown.

The trunnion 6 extends inwardly from the bearing 4. Mounted upon the inward extension of the trunnion 6 and the portion of the sleeve 13 which projects inwardly from the bearing 5 are legs 18 of a support 19 in which is rotatably mounted a flask 20. The inward projection of the trunnion 6 is keyed to one of the legs 18. Thus operation of the piston in the cylinder 10 causes the support 19 to turn between a position in which the flask 20 is generally horizontal, as shown in solid lines in Figure 1, and a position in which the flask is generally vertical, as shown in chain lines in Figure 1. When the support 19 is in the solid line position its left hand end seats upon a portion of the frame 2. When the support is in the chain line position its lower end seats upon a base 21.

Keyed to the inner end of the shaft 14 is a bevel pinion 22. Journaled in downward extensions 23 of the support 19 is a shaft 24 whose axis is parallel to the axis of the flask 20 and to one end of which is keyed a bevel pinion 25 meshing with the bevel pinion 22. Also keyed to the shaft 24 is a pulley 26. Mounted upon the flask 20 is a pulley 27 which is coplanar with the pulley 26. V-belts 28 extend about the pulleys 26 and 27 so that when the shaft 24 turns the flask 20 is rotated. Since the drive for the shaft 24 is coaxial with the trunnion 6 and the bearing sleeve 13 the shaft 24 may be driven in any angular position of the support 19 and, indeed, may be driven during turning of the support 19 between its respective positions. Consequently, it is possible to rotate the flask 20 at all times, when it is in the vertical position, when it is in the horizontal position and when it is in any intermediate position.

The flask 20 is mounted for rotation in bearings 29 in the support 19 and has radial fins 30 for the dissipation of heat. The flask is substantially cylindrical externally but is tapered internally from relatively small diameter at its left hand or upper end to relatively large diameter at its right hand or lower end, viewing the solid line and chain line showings of Figure 1. This is to facilitate stripping of the pipe cast in the mold formed in the flask and to facilitate removal of the used mold forming material (e. g. sand) from the flask.

Mounted above the flask is an overhead track-way 31 along which are adapted to roll trucks 32 and 33. A longitudinally extending bar 34 is connected with both of the trucks 32 and 33 so that the trucks are always spaced the same distance apart and move in unison. The bar 34 is connected at 35 with a piston rod 36 of a piston operating in a cylinder 37. The truck 32 carries a receptacle 38 for receiving mold forming material from a container or bin 39. The bin 39 has an opening 40 in its bottom. Connected with the receptacle 38 is a horizontally extending closure plate 41 whose function is to close the opening 40 at all times except when the receptacle 38 is

positioned directly below it, at which time mold forming material is delivered through the opening 40 into the receptacle 38. The truck 33 carries a vertical cylinder 42 within which operates a piston having a piston rod to which is connected at its lower end a device 43 for stripping the cast pipe from the mold and for assisting in discharging the used mold forming material from the flask.

When the piston in the cylinder 37 is at the left hand end of its stroke, viewing Figure 1, and as the parts are shown in that figure, the receptacle 38 is directly above the flask 20 when the flask is in its upright position. The receptacle has pivoted closure means 44 of clam shell type at its lower end which are operable to permit discharge from the receptacle by gravity of the mold forming material therein which has been received from the bin 39. When the piston in the cylinder 37 is at the right hand end of its stroke the receptacle 38 is positioned directly beneath the opening 40 and the stripper 43 is positioned coaxially with the flask when the latter is in its vertical position.

The frame 2 has a generally horizontal extension 45 which carries a guideway 46 which is parallel with the axis of the flask 20 when the flask is in its generally horizontal position as shown in solid lines in Figure 1. Mounted for travel along the guideway 46 is a carriage 47. Fixedly mounted on the guideway and extending longitudinally thereof is a downwardly facing rack 48. Mounted on the carriage 47 is an electric motor 49 having a shaft 50 to which is keyed a pinion 51 meshing with the rack 48. Travel of the carriage 47 along the guideway is effected by operation of the motor 49 which turns the pinion 51. Since the pinion 51 meshes with the stationary rack 48 it causes the carriage 47 to move along the guideway. The motor 49 may have any suitable control mechanism; limit switches 51a shown purely diagrammatically in Figure 1 may be provided for stopping the motor to prevent overtravel of the carriage 47 in its respective directions of movement.

Mounted upon the carriage 47 for movement relatively thereto transversely of the direction of movement of the carriage along the guideway is a carrier 52. The carrier 52 has a dovetail connection 53 with the carriage 47 which permits movement of the carrier relatively to the carriage in the horizontal direction and perpendicular to the plane of the paper viewing Figure 1. The carriage 47 has fastened thereto a bracket 54 to which is connected a cylinder 55 in which operates a piston having a piston rod 56 connected at 57 with a bracket 58 attached to the carrier 52. Thus movement of the piston in the cylinder 55 causes travel of the carrier 52 relatively to the carriage 47.

Mounted on the carrier 52 are two generally parallel devices for operating upon mold forming material in the flask 20. These devices are a device 59 for removing a portion of the mold forming material in the flask and providing an opening therein and a device 60 for compacting and shaping the mold forming material in the flask. The device 59 comprises a tube 61 in which operates a screw conveyor 62. The screw conveyor 62 is rotated by a shaft 63 carrying pulley 64. Mounted on the carrier 52 is an electric motor 65 whose shaft 66 carries a pulley 67. V-belts 68 are trained about the pulleys 64 and 67 and provide a drive for the shaft 63 and consequently the screw conveyor 62. The con-

veyor turns in a direction to move mold forming material from left to right, viewing Figure 2, an opening 69 being provided in the tube 61 for passage of mold forming material into the tube and an opening 69a being provided in the tube for discharge of mold forming material therefrom. A sweep 69b roughly shapes the enlarged end of the mold where the bell of the pipe is to be cast, the mold forming material intercepted by the sweep entering the tube 61 through the opening 69. Bracing webs 69c aid in supporting the tube 61, compensating for the weakening effect of the openings 69 and 69a. The tube 61 is open at its unsupported or left hand end, viewing Figure 2.

The device 60 is a mandrel which is rotatably carried upon a bearing shaft 70. While the mandrel may be driven it is preferably mounted for rotation through frictional engagement with the mold being formed. The devices 59 and 60 are parallel to each other and parallel to the guideway 46, thereby being adapted upon movement of the carriage 47 along the guideway to enter the flask 20.

Mounted for rectilinear movement upon the frame 2 is a slide 71 carrying an upstanding guide 72 having therein a guide opening 73. The slide 71 is connected at 74 with a piston rod 75 connected with a piston in a cylinder 76 mounted on the frame. The opening 73 is adapted to be aligned with the mandrel 60, the mandrel shaft 70 having a reduced extremity 77 at its forward end adapted when the mandrel has been inserted into the flask to enter the opening 73 whereby the free end of the mandrel is supported and guided. The slide 71 is adapted to be moved to position the guide 72 in a laterally offset out-of-the-way position when material (e. g., molten metal) to be cast is introduced into the mold. Such movement of the slide is effected by movement of the piston in the cylinder 76 downwardly viewing Figure 2.

The frame carries brackets 78 having bearings 79 at their outer ends, and a shaft 80 is journaled for rotation in the bearings. Mounted in the frame is a cylinder 81 containing a piston with which is connected a piston rod 82. The piston rod 82 is connected by a pin 83 with an arm 84 fixed to the shaft 80. Hence movement of the piston and the cylinder 81 causes turning of the shaft 80 through a small angle. The pin connection 83 between the piston rod 82 and the arm 84 may provide for some lost motion to allow for the change in elevation of the lower end of the arm 84 during operation. Fixed to the shaft 80 are two upwardly projecting arms 85 and 86. Each of these arms has in its upper extremity a generally horizontally arranged bolt 87 held in adjustably fixed position by nuts 88.

When the piston in the cylinder 81 is at the right hand end of its stroke, viewing Figure 4, the upper extremities of arms 85 and 86 are in their extreme outward (i. e., left hand) positions. The nuts 88 are adjusted so that when the arms 85 and 86 are in their extreme outward positions, as shown in Figure 4, the noses of the bolts are slightly spaced from the slide 71 and the carrier 52, respectively, when the carriage 47 and the carrier 52 are in the chain line position of Figure 2 and the slide and the carrier are positioned (by the pistons in the respective cylinders 76 and 55 being at the extreme upper ends of their strokes, viewing Figure 2) so that the guide opening 73 and the mandrel 60 are co-

axial with the flask 20 when the flask is in its horizontal position. The bolt carried by the arm 86 can engage the carrier 52 only when the carriage 47 is in its advanced position, i. e., the chain line position of Figure 2. But the carrier 52 is positioned so that the mandrel 60 is coaxial with the flask 20 when the piston in the cylinder 55 is at the extreme upper end of its stroke, viewing Figure 2, the flask then being in its horizontal or solid line position.

The function of the shaft 80 and its associated mechanism is to position the carrier 52 and the slide 71 in the downward direction, viewing Figure 2, in such manner that the mandrel 60 and the guide opening 73 remain coaxial with each other, but to move the mandrel to a position somewhat eccentric to the flask 20 so that the mandrel will compact and shape the mold forming material in the flask to form a cylindrical mold of desired diameter. During the compacting and shaping action the mandrel will turn due to its frictional contact with the mold being formed. The extent of the movement given the slide 71 and the carrier 52 by turning of the shaft 80 depends upon the distance which the piston in the cylinder 81 moves. This distance may be determined by the operator through a gauge connected with the piston rod, or a stop 84a may be provided cooperating with the arm 84, the stop being adjustable to limit turning movement of the arm 84 in the clockwise direction, viewing Figure 4, to the extent necessary to cause the desired amplitude of movement of the mandrel and guide eccentrically of the flask.

The mandrel 60 is of somewhat smaller diameter than the tube 61. When the tube 61 is inserted into the flask it removes a portion of the mold forming material therein and provides an opening axially of the flask. When the piston in the cylinder 55 is in its extreme lower position, viewing Figure 2, the tube 61 is disposed axially of the flask. After the conveyor has removed a portion of the mold forming material in the flask and provided an opening therein the mandrel is moved axially into the opening, and after the mandrel is in place with the shaft extremity 77 within the guide opening 73 it is moved eccentrically of the flask to the extent necessary to produce a cylindrical mold of the desired diameter.

At its supported end the mandrel 60 is enlarged as shown at 89 to form the enlarged end of the mold where the bell of the pipe is to be cast and the mandrel also has a stop plate 89a in the form of a radial flange whose diameter is somewhat greater than the internal diameter of the flask 20 at its right hand end viewing the solid line showing of Figure 1. The stop plate 89a is faced at its left hand face viewing Figure 1 with bearing material and when the mandrel is in operative position within the flask and mold the stop plate bears against the end of the flask. The mandrel has an enlargement 106 which forms a corresponding recess in the mold to form the spigot end of the cast pipe section. After the mandrel has been withdrawn from the mold a core is inserted, the core being shown in Figure 6 and designated 90. The core is fitted into the mold at the complementary conical surfaces 91 of the core and mold, the forward portion 92 of the core being shaped to cooperate with the mold and spaced from the mold so that when the material being cast is introduced it will flow into the cavity 93 between the mold and the core to form the bell of the pipe.

There is provided a slide 94 operable in a slot 95 in the support 19 and which is movable to three positions to perform three different functions. The slide has an imperforate portion 5 adapted to entirely close the end of the flask, a core holding portion shown in cross section in Figure 6 adapted to hold the core in place while permitting venting thereof and another portion having a large opening substantially greater than the diameter of the plate 89a. When the flask is to be filled with mold forming material the imperforate portion of the slide 94 is positioned over the end of the flask. When the core is to be held in place the core holding portion is positioned over the end of the flask. The core holding portion has a central venting opening 96 permitting venting of the core. When the devices 59 and 60 are in operation and when the cast pipe is to be removed from the flask and the used mold forming material is to be expelled the slide 94 is moved to its third position which leaves the end of the flask open and unobstructed.

Means are provided for maintaining the slide 94 in each of its three positions. The slide has in its upper edge three similar drilled openings 97 respectively cooperable with a latch pin 98 to hold the slide in its respective positions. The frame has an extension 99 having an opening 100 for guiding the pin 98. Connected with the extension is a bracket 101 having an opening 102 through which the pin 98 passes, the head 103 of the pin normally resting on top of the bracket 101. A collar 104 is fixed to the pin 98 and a compression coil spring 105 is interposed between the bracket 101 and the collar 104. Thus the spring urges the pin downwardly, but the pin may be drawn upwardly against the action of the spring to remove it from each of the openings 97 in the slide 94. When it is desired to move the slide 94 from one position to another the pin 98 is raised out of the opening 97 in which it has been positioned, the slide is moved to its new position and the pin is allowed to enter the opening 97 positioning the slide in its new position, the pin being maintained in operative position by the spring 105.

I shall now describe a complete cycle according to my invention and illustrate the operation of the apparatus. The flask 20 being entirely empty, the slide 94 is moved to the position in which its imperforate portion closes the end of the flask. The flask is disposed in its vertical position as shown in chain lines in Figure 1. The receptacle 38 with a measured amount of mold forming material therein (preferably an amount sufficient to fill the flask) which has been received from the bin 39 through the opening 40 is positioned above the flask in the position shown in Figure 1, and the mold forming material is discharged from the receptacle 38 into the flask, this being accomplished by raising the clam shell closure means 44. Rotation of the flask is commenced either before or during or immediately following the delivery of the mold forming material thereinto. While the flask continues to rotate it is turned from its vertical position as shown in chain lines in Figure 1 to its horizontal position as shown in solid lines in Figure 1. While rotation of the flask continues the slide 94 is moved to the position in which the end of the flask is rendered completely open. The carrier 52 is then moved to position the tube 61 axially of the flask and with the conveyor 62 operating the carriage 47 is advanced toward the left, viewing Figures 1 and 2, to move the tube 61 with

the conveyor 62 turning therewith into the flask to remove a portion of the mold forming material in the flask and provide an opening therein. The operation is rapid, the carriage 47 being moved to the left until the conveyor has completely penetrated the flask, whereupon the carriage is moved back to the position in which the conveyor is disposed entirely outside of the mold. The carrier 52 is then moved to position the mandrel 60 coaxially of the mold. Then the carriage 47 is again advanced, the mandrel 60 entering the opening in the mold which had previously been made by the conveyor. After the mandrel has been advanced so that the shaft extremity 77 is positioned within the opening 73 the mandrel is moved eccentrically by operation of the piston in the cylinder 81 as above described to compact and shape the mold forming material in the flask. After the mold forming material has been compacted and shaped the mandrel is returned to its coaxial position relatively to the flask, when it is withdrawn. Thereupon the core 90 is inserted and the slide 94 is moved to its core holding position as shown at Figure 6. The slide 71 is drawn downwardly, viewing Figure 2, to position the guide 72 out of the way, and molten metal is introduced into the rotating mold through a pouring spout indicated in Figure 1 in chain lines at 73a to cast a length of pipe. A cast length of pipe is shown at 107 in Figure 6.

After the molten metal has solidified the flask is turned to its vertical position, the piston in the cylinder 37 is moved to the right hand end of its stroke to position the cylinder 42 coaxially with the flask, and the piston in the cylinder 42 is moved downwardly to strip the cast pipe from the mold and eject the used mold forming material to clean out the flask for the succeeding operation. When the cylinder 42 is disposed above and in axial alignment with the vertically positioned flask the receptacle 38 is positioned beneath the opening 40 of the bin 39, whereby to uncover that opening and allow mold forming material to be delivered by gravity into the receptacle 38. When the receptacle 38 is next moved to the left, viewing Figure 1, into position to deliver the mold forming material into the flask the plate 41 closes the opening 40 and maintains that opening closed until the succeeding cycle of operations.

Figures 7 and 8 show a modified form of structure. In the modified structure the motor for rotating the flask is mounted on the flask support, eliminating the bevel gear drive of the structure of Figures 1 to 6, inclusive. In Figures 7 and 8 parts corresponding to parts shown in Figures 1 to 6, inclusive, are designated by the same reference numerals but each having a prime affixed. The base or frame 2' has parallel spaced upward projections 3' carrying coaxial bearings 4' and 5'. Journaled in the bearings 4' and 5' is a trunnion shaft 6'. Keyed to the trunnion shaft 6' at approximately its midpoint is an arm 7' whose outer end is pivoted at 8' to a piston rod 9' connected with a piston in a cylinder 10' pivotally mounted at 11' in brackets 12'. The piston in the cylinder 10' is operated by any suitable fluid under pressure. Movement of the piston in the cylinder swings the arm 7' about the axis of the trunnion shaft 6', and since the arm is keyed to the trunnion shaft this results in turning the trunnion shaft 6' in the bearings 4' and 5'.

Keyed to the trunnion shaft 6', one between the bearing 4' and the arm 7' and the other between the bearing 5' and the arm 7', are legs 18' of a

support 19' in which is rotatably mounted a flask 20'. Operation of the piston in the cylinder 10' causes the support 19' to turn between a position in which the flask 20' is generally horizontal, as shown in solid lines in Figure 7, and a position in which the flask is generally vertical, as shown in dash lines in Figure 7. When the support 19' is in the solid line position its left hand end seats upon a portion of the frame 2'. When the support is in the dash line position its lower end seats upon a base 21'.

Mounted on the support 19' is a bracket 108 carrying an electric motor 17' whose shaft 14' is parallel to the axis of the flask 20'. Keyed to the motor shaft 14' is a pulley 26'. Mounted upon the flask 20' is a pulley 27' which is coplanar with the pulley 26'. V-belts 28' extend about the pulleys 26' and 27' so that when the motor 17' is in operation the flask 20' is rotated. Since the means for rotating the flask is mounted on the support which carries the flask, the flask may be rotated at all times, when it is in the vertical position, when it is in the horizontal position, and when it is in any intermediate position, as well as when it is moving about the axis of the trunnion shaft 6' from one position to another.

The flask 20' is mounted for rotation in bearings 29' in the support 19' and has radial fins 30' for the dissipation of heat. The flask may to all intents and purposes be the same as the flask 20 of the form of structure shown in Figures 1 to 6, inclusive.

The frame 2' has a generally horizontal extension 45' which carries a guideway 46' which is parallel with the axis of the flask 20' when the flask is in its generally horizontal position as shown in solid lines in Figure 7. Mounted for travel along the guideway 46' is a carriage which may to all intents and purposes be the same as the carriage 47; and the carriage may carry a carrier and associated mechanism which may to all intents and purposes be the same as the carrier 52 and associated mechanism.

Mounted for rectilinear movement upon the frame 2' is a slide 71' carrying an upstanding guide 72' having therein a guide opening 73'. The slide 71' is maintained in position and guided for movement transversely of the frame by guides 109. The slide 71' is connected through a downward projection 110 with a piston rod connected with a piston in a cylinder 76' mounted in the frame. The opening 73' is adapted to be aligned with a mandrel and functions in the same manner as the opening 73 of Figures 1 and 2.

The remainder of the operating mechanism may be similar to that of the structure shown in Figures 1 to 6, inclusive, elements 78' to 84', inclusive, being analogous to elements 78 to 84, inclusive, of the first described structure. In Figures 7 and 8 portions of the operating mechanism are omitted to aid in clarity of disclosure of the portions shown.

The flask support is provided with a slot 95' in which a slide similar to the slide 94 may be operated. The slide may be maintained in its various positions by a latch pin 103'.

The general operation of the structure of Figures 7 and 8 is the same as that of the structure of Figures 1 to 6, inclusive.

While I have illustrated and described certain present preferred methods of practicing the invention it is to be distinctly understood that the invention is not limited thereto but may be otherwise variously embodied and practiced within the scope of the following claims.

I claim:

1. A foundry process comprising disposing an elongated flask in generally upright position, while the flask is so disposed introducing mold forming material thereinto through the upper end thereof, compacting the mold forming material within the flask to form a hollow mold, disposing the flask in generally horizontal position, rotating the flask, introducing molten material into the mold in the rotating flask to form by centrifugal casting a hollow article, disposing the flask with the article therein in generally upright position with the end uppermost which was uppermost when the mold forming material was introduced thereinto and with the flask so disposed discharging the article from the flask through the lower end thereof, all the foregoing operations being performed at a single station.

2. A foundry process comprising disposing an elongated flask in generally upright position, while the flask is so disposed introducing mold forming material thereinto through the upper end thereof, compacting the mold forming material within the flask to form a hollow mold, disposing the flask in generally horizontal position, rotating the flask, introducing molten material into the mold in the rotating flask to form by centrifugal casting a hollow article, disposing the flask with the article therein in generally upright position with the end uppermost which was uppermost when the mold forming material was introduced thereinto, with the flask so disposed discharging the article and mold material from the flask through the lower end thereof and while the flask is still disposed with the end uppermost which was uppermost when the mold forming material was introduced thereinto introducing mold forming material thereinto through the upper end thereof for the formation of another mold, all the foregoing operations being performed at a single station.

3. A foundry process comprising disposing an elongated flask in generally upright position, while the flask is so disposed introducing mold forming material thereinto through the upper end thereof, while the flask is so disposed commencing rotation of the flask, while rotating the flask turning the flask from generally upright position to generally horizontal position, compacting the mold forming material within the flask to form a hollow mold, while rotating the flask introducing molten material into the mold to form by centrifugal casting a hollow article, disposing the flask with the article therein in generally upright position with the end uppermost which was uppermost when the mold forming material was introduced thereinto and with the flask so disposed discharging the article from the flask through the lower end thereof, all the foregoing operations being performed at a single station.

LOYAL L. JOHNSTON.
